[57] CLAIM

The ornamental design for a skid steel loader vehicle, as shown and described.

DESCRIPTION

FIG. 1 is a right front perspective view of a skid steer loader vehicle, showing my new design;

FIG. 2 is a right rear perspective view thereof;

FIG. 3 is a right side elevational view thereof;

FIG. 4 is a front perspective view thereof with the bucket removed for clarity;

FIG. 5 is a left side elevational view thereof;

FIG. 6 is a rear perspective view thereof;

FIG. 7 is a right rear perspective view thereof, with the boom assembly in the raised position;

FIG. 8 is a front perspective thereof, with the boom assembly in the raised position;

FIG. 9 is a rear perspective thereof, with the boom assembly in the raised position; and

FIG. 10 is an enlarged top perspective view thereof.
